VISIBLE LUBRICANT DISPENSING MEANS

Guy A. Hill, Wichita, Kans.

Application May 26, 1932. Serial No. 613,599

2 Claims. (Cl. 221—100)

My invention relates to a visible lubricant dispensing means.

The object of my invention is to associate the said means with a clear vision pump and carried 5 thereby.

A further object of my invention is to provide a simple and efficient means to attach the visible dispensing means to a clear vision pump.

These and other objects will hereinafter be more 10 fully explained, reference being had to the accompanying drawing forming a part of this specification, and in which like characters will apply to like parts in the different views.

Referring to the drawing:—

15 Fig. 1 is an elevation of the upper portion of a clear vision pump with the visible lubricant dispensing means attached.

Fig. 2 is a sectional view of a fragmentary portion of the clear vision pump and visible lubricant 20 dispensing means.

Fig. 3 is a plan view of the top head of the tube.

Fig. 4 is a side view of the head of the tube.

25 Fig. 5 is an inverted plan view of the lower head of the tube.

Fig. 6 is a top plan view of the expansion plate.

My invention consists of a transparent tube 1 functioning as a container for oil as a lubricant.

30 Spaced on the tube longitudinally is a plurality of graduations 2 being numbered consecutively from the top downward. Each space between graduations contemplates one ounce or other proportions as desired.

Secured to the lower end of the tube is a head 3 and to the upper end a head 4, the said head being tensioned to their respective ends of the tube by a rod 5 axially extending thru the tube and tensioned by a nut 6, the other end having a head 7 to abut on the lower head oil tight. Each of the

40 said heads are bored to receive its respective end of the tube snugly, and having in the bottom thereof a gasket packing 8 on which the ends of the tube will rest as an oil tight sealing means. The lower head has a pet cock 9 outwardly extending and thru which the lubricant is dispensed.

An end portion of head 3 is arcuate, the radius of which is drawn from the axis of the clear vision pump, and being so arranged it will conform to the periphery of the container 10 of the clear vision pump. Spaced from the edge thereof is a groove 11 paralleling the end and adapted to seat on an annular tongue 12 positioned on the lower head of the said container 10, the latter arrangement being the method of securing my visible lubricant dispensing means at the lower end. The

upper end is secured by a plate 13 tensioned by a pair of screws 14 pivotally engaging in their respective ends of the plate and threadedly engaging in the threaded apertures 15 oppositely positioned in the upper head 4. Each of the said screws have a knurled head 16 as turning means therefor, functioning as a strut to snugly engage between the upper and lower heads of the clear vision pump container.

Positioned on the upper side at each end of 65 plate 13 is a flexible disc 17 that is preferably made of rubber to avoid movement as the same is frictionally engaged.

In the upper head is an aperture 18 as shown by dotted lines and thru which the tube is filled 70 with lubricant. The said aperture is threaded to receive a threaded stud 19 as closing means therefor, and to avoid a vacuum when lubricant is being drawn from the tube, I have provided an orifice 20 axially positioned in the stud as a vent. 75

While I have shown my invention as described as being attached to a clear vision pump I do not wish to be restricted to such alone as the same may be applied to other style of pumps, or may be supported otherwise by proper bearings, and between which the strut arrangement will function. However, the purpose is to advertise by visible means and sell lubricant to be mixed with gasoline and inasmuch as the preferred oil is unflammable, it serves well as a lubricant for the valves and tends to dissolve carbon deposit, and such other modifications may be employed as lie within the scope of the appended claims.

Having fully described my invention what I claim as new and desire to secure by Letters Patent is:—

1. In a visible dispensing means for lubricant, in combination with a clear vision pump having 95 outwardly projecting head members, a transparent tube having graduation marks spaced therealong and being numbered consecutively from the top downward, a head seated on the lower end of the tube and having a groove to 100 engage with the extension of the lower head of the clear vision pump, and a pet cock positioned in the head, a head on the other end of the tube, said head having a pair of threaded apertures oppositely positioned therein, and means to compress the heads to snug engagement with their respective ends of the tube, a strut element carried by the upper head consisting of a plate and a screw threadedly engaging in each of the apertures, the plate to frictionally engage on the 105 110

under side of the upper head of the clear vision pump and tensioned thereto by screws.

2. In a visible lubricant dispensing means of the class described and carried in parallelism with a container of a clear vision gasoline pump having an upper and lower head, a graduated clear vision tube, and a head positioned on the upper and lower ends thereof, and means to secure the same oil tight, the lower head having a pet cock, 10 and means to seat on the lower head of the clear

vision pump container, the upper head having accessible means to the interior of the tube for filling the same with lubricant and being provided with an orifice to avoid a vacuum, a plate and screw elements carried by the upper head as expanding means to frictionally engage the plate with the upper head of the clear vision pump container, all as and for the purpose specified.
